CLAIM

The ornamental design for a toilet plunger with brush as shown and described.

DESCRIPTION

FIG. 1 is a perspective view of a toilet plunger with brush showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a perspective view of a toilet plunger and a brush of the toilet plunger with brush, shown separately for ease of illustration and in an open configuration;

FIG. 11 is another perspective view thereof;

FIG. 12 is a left side elevational view thereof;

FIG. 13 is a front elevational view thereof; and,

FIG. 14 is a top plan view thereof.

The broken lines in the drawings depict portions of the toilet plunger with brush that form no part of the claimed design.
